John L. Morris
Attorney

Patented Feb. 19, 1929.

UNITED STATES PATENT OFFICE.

CHESTERFIELD G. MARHOFF, OF CHICAGO, ILLINOIS.

DRIP-CUP ATTACHMENT FOR SPIGOTS.

Application filed March 29, 1928. Serial No. 265,590.

This invention relates to improvements in drip cup attachments for percolator spigots, one object of this invention being the provision of a device of this kind which is readily attachable to the valve stem of any of the present type percolator spigots and provides a means for catching the undesirable drip from the spigot after liquid has been drawn therefrom in filling a cup and after the valve has been closed.

Another object of this invention is the provision of a device of this kind which is adapted for use upon a two-way opening spigot, thus providing a simple, durable and inexpensive device of this character and one which is thoroughly efficient and practical in use.

In the accompanying drawings:—

Figure 1 is a side elevation of a part of a percolator adjacent the spigot portion thereof showing the present device in drip-receiving position;

Figure 2 is a top plan view showing the device in full lines when in drip-receiving position, and in dotted lines when in cup-filling position, the body of the percolator being shown in cross-section;

Figure 3 is a top plan view of the cup-holding attachment per se;

Figure 4 is a longitudinal sectional view through the lower end of the spigot stem and the present device; and

Figure 5 is a view similar to Figure 3 of a modified form.

Referring to the drawings, the numeral 6 designates the percolator proper which is provided with the spigot or faucet 7 having the hand-actuated valve stem 8, the reduced end 8' of which is threaded and engages the usual nut 9 for holding the valve in proper seated position.

The cup-holding device 10 is made from a single piece of metal and is provided with the enlarged central portion 11 having either the angular opening 12, as shown in Figure 3, or the circular opening 12', as shown in Figure 5, for engaging the lower end of the stem 8 and to be held in place by means of the nut 9, as illustrated in Figures 1 and 4. This member is provided with the oppositely extended and bent arms 13 and 13' which terminate in the apertured enlarged terminals 14 and 14'.

for, in turn, removably receiving the drip-cups 15 and 15'.

These cups 15 and 15' are preferably made of metal, but may be made of glass, china, or any type of material that may be deemed desirable. If of wax-paper, a cup is provided that can be thrown away without washing.

From the foregoing description, taken in connection with the drawings, it is evident that with a device applied as illustrated in the drawings, when the valve stem 8 is in valve closing position, one of the drip-cups 15 or 15' is presented to the outlet end of the spigot 7 so that any drip therefrom after the cup has been filled is received in the cup and thereby prevented from falling into the tray or upon the table.

Where a single-way valve stem is employed as shown, a single cup is all that is necessary, but as most percolators are provided with a double-way opening valve, it is desirable that the two cups and the present device 10, as illustrated, be employed.

The spring 17 may be placed upon the spigot between the lower end of the valve and the drip device.

The drip device may be made of any desired material suitable for use, such as celluloid fibre, bakelite, etc., and where found necessary, the arms may be flat, if it is found that the outlet of the spigot is shorter.

This device can be used upon any type of spigot when it is desired to catch the drip, such as percolators, urns, etc.

I claim:—

1. A device of the character described for attachment to the spigot of a percolator made from a single piece of metal and provided with a stem-receiving portion, and two oppositely disposed enlarged apertured ends whereby two drip cups may be removably supported thereby.

2. A drip cup holding device made from a single piece of flat metal and provided with an enlarged apertured portion for engaging the stem of a spigot, two outwardly and downwardly bent apertured terminals, and two cups detachably fitting in said terminals.

In testimony whereof I have hereunto set my hand.

CHESTERFIELD G. MARHOFF.
